US00D488171S

(12) **United States Design Patent** (10) Patent No.: **US D488,171 S**
Juncker et al. (45) Date of Patent: ** Apr. 6, 2004

(54) **TRACK APPARATUS FOR USE IN PLACE OF A VEHICLE WHEEL**

(75) Inventors: **Kenneth J. Juncker**, Mt. Vernon, IN (US); **Jamsheed Reshad**, Newburgh, IN (US); **Glenn W. Kahle**, Franklin, MO (US)

(73) Assignee: **AgTracks, Inc.**, Mt. Vernon, IN (US)

(**) Term: **14 Years**

(21) Appl. No.: **29/157,380**

(22) Filed: **Mar. 18, 2002**

(51) LOC (7) Cl. **15-03**

(52) U.S. Cl. **D15/28**

(58) Field of Search **D15/10, 22-26, D15/28; 305/129, 136; 180/9.54, 9.21**

Primary Examiner—Mitchell Siegel

(74) Attorney, Agent, or Firm—Jansson, Shupe & Munger, Ltd.

(57) **CLAIM**

The ornamental design for a track apparatus for use in place of a vehicle wheel, substantially as shown and described.

DESCRIPTION

FIG. 1 is a perspective view;

FIG. 2 is a front elevation;

FIG. 3 is a rear elevation;

FIG. 4 is a side elevation;

FIG. 5 is a top view; and,

FIG. 6 is a bottom view.

The broken line disclosure is for illustrative purposes only and forms no part of the claimed design.
